UNITED STATES PATENT OFFICE.

CARL ALBERT HARTMANN, OF BERLIN-SIEMENSSTADT, GERMANY, ASSIGNOR TO SIEMENS & HALSKE AKTIENGESELLSCHAFT, OF SIEMENSSTADT, NEAR BERLIN, GERMANY.

ACOUSTIC DIAPHRAGM.

Application filed May 27, 1927, Serial No. 194,856, and in Germany October 22, 1926.

This invention relates to an improved type of acoustic diaphragm for use in telephone receivers and transmitters and the object of the invention is to produce a diaphragm 5 which is very light in weight and at the same time most efficient.

It has been proposed previously to use very thin metal foil as a diaphragm, the reason being that it was necessary to make 10 the vibrating systems as light as possible. When made singly in the laboratory such diaphragms can be made, but as a commercial article of manufacture they are not 15 resistant enough and require complicated auxiliary devices which make manufacture very difficult.

This invention overcomes this difficulty, and by proceeding with the conviction that 20 lightness of the vibrating system is an essential feature, the present diaphragm is made of material having a very low specific gravity, like paper, silk tissue, etc. It is therefore possible to make such diaphragms substantially thicker and still keep them to the 25 same weight per unit area of about one milligram per cubic centimeter. In this instance papers of 0.005 thickness have sufficient strength so that a diaphragm made from it can be satisfactorily constructed as a factory article without any special devices being 30 employed.

A diaphragm constructed of the above material, will of course, have no magnetic or electrical conductivity, which is one of the 35 first requisites when used in telephone receivers or transmitters. According to the invention, this diaphragm is therefore subjected to a treatment which imparts electric or magnetic conductivity to it. For this 40 purpose use is made of the otherwise undesirable property of absorbing moisture to make the material electrically conducting. This property may be assisted or produced by impregnating the diaphragm with hygroscopic salts or solutions, calcium chloride 45 (CaCl_2) for instance.

A paper diaphragm so treated can be used with success in the unstretched condition in condenser transmitters or telephone receivers. Hitherto in order to place the natural 50 frequency of the diaphragm the other side of the range of audibility, it was necessary to either stretch the diaphragm very tightly or allow the diaphragm to cushion a certain

volume of air; at times both means were 55 used at the same time. When using the first method it is necessary to use such intense stretching forces that as a rule the elastic limit of the diaphragm is exceeded even though it consists of steel, before a natural 60 vibration of 10000 Hertz is reached. When using the second expedient, such small volumes of air are necessary that the ratio of surface to the volume of the air cushion exceeds the highest admissible value; this is 65 characterized by the fact that the volume changes are no longer adiabatic but that during a compression, heat is noticeably led off. The air cushion then acts no longer in a manner which increases the natural frequency, but with an increasingly damping 70 action.

Owing to these necessarily small air volumes other difficulties also occur, especially during the transmission of low frequencies. 75 As is known, all notes of low frequency, say under 100 Hertz, with subjectively equal sound intensities have up to twice the amplitude of the sounds of higher frequencies. Such amplitudes are, however, considerably 80 impaired by an air cushion of the usual thickness of a few tenths or even hundredths of a millimeter; under certain circumstances the diaphragm may even hit against the back of the air cushion.

With an unstretched diaphragm according to the invention, the natural vibration of the slight weight may be easily shifted beyond the range of audible frequencies. When using an air cushion the danger of distortion 90 of the low frequencies and of the striking of the diaphragm is eliminated with certainty by the fact that substantially thicker air cushions, say 5 millimeters thick can be used.

Further the system is much more sensitive than those formerly known as the air cushion, being thicker, the tone is softer and the diaphragm can make greater amplitudes owing to its lightness and greater freedom 95 of motion.

The electrical conductivity of the diaphragm mass can also be obtained by applying an exceedingly thin layer of finely divided conducting material like graphite.

The use of the new diaphragm in electro-magnetic apparatus such as telephone receivers and loud speakers can be effected 105 in known manner by applying a magnetic

armature to the diaphragm. Owing to the very small mass of diaphragm which is to be set in motion, the armature itself may be made very light and small, so that its mass only causes a slight increase of the average mass of the vibrating system. For a given diaphragm diameter of 40 millimeters such as is usual for normal telephones, a diaphragm with fairly thick paper of 0.013 millimeters and specific gravity of approximately 1 will weigh about 18 milligrammes. For this diaphragm an iron armature of 5 millimeters diameter and 0.05 millimeters thick is perfectly adequate, this weighing only about 8 milligrammes. The armature weight is thus less than half of the diaphragm weight so that the advantageous effect of the light diaphragm is scarcely impaired.

According to the invention it is further possible to dispense with the armature altogether by making the diaphragm magnetically conductive by impregnating it with a para-magnetic salt solution say of ferric chloride (Fe_2Cl_6).

When using very thin papers of about 0.006 millimeters any small holes which are apt to be present deleteriously affect the apparatus as they spoil the efficiency of the air cushion. This can be remedied easily by impregnating the paper with a weak solution (about 5%) of collodion.

Fig. 1 shows a front view of the diaphragm, partly in section.

Fig. 2 shows a cross sectional view of the diaphragm.

The accompanying single sheet of drawings illustrates the invention. It shows, on an enlarged scale, a cross section and a front view of the disclosure. Reference numeral 1 shows a diaphragm of paper or other suitable material as specified in the foregoing

description; numeral 2 indicates the treatment of the diaphragm with a chemical such as calcium chloride ($CaCl_2$) in order to impart electrical properties thereto; 3 indicates a deposit of collodion; and reference numeral 5 a magnetic armature attached to the diaphragm.

What is claimed is:

1. An acoustic diaphragm for telephones or the like, comprising a sheet of fibrous material impregnated with a solution of calcium chloride to impart electric properties thereto. 50
2. An acoustic diaphragm for telephones or the like, comprising a sheet of fibrous material with highly hygroscopic properties, said hygroscopic properties utilized for impregnating said diaphragm with a solution of calcium chloride to impart electric properties thereto. 55
3. An acoustic diaphragm for telephones or the like consisting of a disk of fibrous material evincing hygroscopic properties and impregnated with a solution of calcium chloride to impart electrical conducting properties to said diaphragm. 60
4. An acoustic diaphragm for telephones or the like, comprising a sheet of paper impregnated with a solution to impart electrical properties thereto and coated with a weak solution of collodion to make said diaphragm air-tight. 70
5. An acoustic diaphragm for telephones or the like, comprising a sheet of fibrous material impregnated with a solution of calcium chloride to impart electrical properties thereto and coated with a weak solution of collodion to make said diaphragm air-tight. 75

In witness whereof, I hereunto subscribe my name this 22nd day of April, A. D. 1927.

CARL ALBERT HARTMANN.
